UNITED STATES PATENT OFFICE.

CHARLES HENRY WATERMAN, OF PRIEST RIVER, IDAHO, ASSIGNOR OF ONE-HALF TO
ROSETTA WATERMAN, OF PRIEST RIVER, IDAHO.

CYCLE MERRY-GO-ROUND.

1,261,197.

Specification of Letters Patent.

Patented Apr. 2, 1918.

Application filed October 11, 1917. Serial No. 195,966.

To all whom it may concern:

Be it known that I, CHARLES H. WATERMAN, a citizen of the United States, residing at Priest River, in the county of Bonner and State of Idaho, has invented certain new and useful Improvements in Cycle Merry-Go-Rounds; and I do declare the following to be a full, clear, and exact description of the invention, such as will enable others skilled in the art to which it appertains to make and use the same.

This invention relates generally to wheeled toys, and more particularly to certain and useful improvements in what may be termed cycle merry-go-rounds.

The primary object of the invention is to provide a small merry-go-round which may be set up quickly and easily at almost any place, and which is propelled by the occupant or rider.

Another object of the invention is to provide an occupant propelled miniature merry-go-round, certain parts of which are detachably connected together so that when not in use, the merry-go-round can be taken apart and packed or stored away in comparatively small space.

Another object of the invention is to provide a device of this character which will be extremely simple, strong, durable and inexpensive in construction, one which will be efficient and reliable in operation, and well adapted to the purpose for which it is designed.

With these and numerous other objects in view, the invention consists of certain novel features of construction, and the combination and arrangement of parts as will be hereinafter fully described and claimed.

In the accompanying drawings forming a part of the application, and in which similar reference characters are used to designate like parts throughout the several views, Figure 1 is a top plan view of a device constructed in accordance with this invention.

Fig. 2 is a bottom plan view of the same;

Fig. 3 is a sectional view taken on the plane indicated by the line 3—3 of Fig. 1;

Fig. 4, is a similar view taken on the plane indicated by the line 4—4 of Fig. 3;

Fig. 5 is a similar view taken on the plane indicated by the line 5—5 of Fig. 3; and

Fig. 6 is a side view of the upright post,

showing the manner in which the sweep bar is connected to the same, said bar being 55 shown in section.

Referring more particularly to the drawings, the numeral 1 designates a post which is square shaped in cross-section, and to each of the sides of which is secured a diagonal 60 leg or brace 2. Thus four of these legs are provided, and they extend in different radial directions from the post 1 to support said post in an upright position. Extending centrally from the upper end of the post 1 is 65 a cylindrical pivot stud or portion 3. This stud or portion 3 is of less diameter than that of the post 1 so as to provide the latter with shoulders 4 at its upper end for the purpose to be hereinafter described. Ex- 70 tending through the upper end of the stud 3 is an opening which receives a suitable pin 5.

The numeral 6 designates a sweep bar. This bar is made of flat and comparatively 75 wide material, and is provided with an aperture 7 at one of its ends. This end of the bar 6 is adapted to rest upon the shoulder 4 of the post 1, the stud 3 extending through the aperture 7 and prevented from being 80 relatively disengaged from the same by means of the pin 5 as clearly shown in Fig. 6 of the drawings.

The other end of the bar 6 rests upon and carries a velocipede designated as an entirety 8. The frame of the velocipede 8 consists of two flat plates 9 and 10 having their adjacent ends screwed or otherwise suitably secured to the angularly arranged outer sides of a block 11 which is secured to the 90 sweep bar 6 near the last mentioned end thereof and which is disposed and extends beneath the same. By having the plates 9 and 10 secured to the angularly arranged sides of the block or connector 11 the plates 95 are arranged angularly with respect to each other.

Secured to the forward plate 9 and having its arms disposed on opposite sides of the same is a fork 12, the shank portion of the 100 same carrying a cross handle bar 13, while the arms of the fork or upright member 12 extend below the lower edge of plate 9 and are provided at their free ends with suitable bearings for receiving the axle of a drive 105 wheel 14. If desired, the lower edge of the

plate 9 may be cut away or notched as shown at 15 to accommodate the upper edge of the wheel 14 which is disposed in the same vertical plane as the plate. The reference numerals 16 represent arms which are connected to the axle of the driving wheel and which are provided with pedals 17 for an obvious purpose.

Disposed on opposite sides of the rear plate 10 and extending below the lower edge of the same is a pair of vertical bars 18. The lower ends of these bars 18 are provided with bearings for receiving the axle of a ground wheel 19 therein. This plate 10 is also cut away or notched as shown at 20.

As clearly illustrated in the drawings the outer end of the sweep bar 10 extends across the intermediate portions of the velocipede and forms a seat for the same. If desired the connection between the bar 6 and the velocipede may be made more rigid by a diagonal brace 21 which has its lower end secured to the lower end of the connector 11 and its other end secured to the lower side of the bar 6.

The plates 9 and 10 are here shown as being shaped and painted to represent the figure of a horse. However, this is not essential.

In using the device a person sits upon the bar 6 straddling the velocipede and drives the pedals 17 in the well-known manner. The post 1 being relatively immovable will cause the bar 6 to move around it in a circle as the velocipede is driven. By having the two wheels of the velocipede disposed angularly with respect to each other, they will travel in a circle, and there will be no tendency for the post to be slid over the ground or upset.

When the device is not in use the pin 5 may be withdrawn and the sweep bar 6 disconnected from the stud 3. The parts may then be stored away in a comparatively small space.

From the foregoing description, taken in connection with the accompanying drawings, the construction, use and operation of the device will be readily understood without a more extended explanation.

As various changes in form, proportion, and in the minor details of construction may be resorted to without departing from the spirit of this invention, it is to be understood that I do not wish to be limited to the construction herein shown and described other than as claimed.

I claim:

1. The combination of a ground-wheel, means including pedals for rotating said ground-wheel, a fork carried by said ground-wheel, a sweep having a relatively flat and broad seat-forming portion at one end and having its other end pivotally mounted, and a vertically disposed plate

having a relatively long and thin edge rigidly secured to the under side of said relatively flat and broad portion of the sweep, said fork being rigidly secured to said plate.

2. The combination of a ground-wheel, means including pedals for rotating said ground-wheel, a fork carried by said ground-wheel, a sweep having a relatively flat and broad seat-forming portion at one end and having its other end pivotally mounted, and a vertically disposed plate having a relatively long and thin edge rigidly secured to the under side of said relatively flat and broad portion of the sweep, said fork being rigidly secured to said plate in spaced relation to said seat-forming end portion of said sweep.

3. The combination of a pair of plates, a sweep having a relatively flat and broad seat forming portion, means for securing said plates to the under side of said seat-forming portion in angular relation to said under side and in angular relation to one another, a member to which said sweep is pivotally connected, a ground-wheel connected to one of said plates, an upright member rigidly secured to the other of said plates, a wheel rotatably secured to said upright member, means to rotate the last said wheel, and a handle-bar rigidly connected to said upright member.

4. In a device of the class described, the combination of an upright post, a flat and comparatively wide sweep bar having one end resting upon and pivotally connected to said post, a block secured to said bar near the other end thereof and disposed and extending below the same, said block being provided with a pair of angularly arranged outer sides, a pair of angularly arranged plates secured at their adjacent ends to said angularly arranged sides of said block and one extending forward and the other rearward of said bar, a driving wheel carried by the forward plate and a ground wheel carried by the rear plate.

5. In a device of the class described, the combination of an upright post, a flat and comparatively wide sweep bar having one end resting upon and pivotally connected to said post, a block secured to said bar near the other end thereof and disposed and extending below the same, said block being provided with a pair of angularly arranged outer sides, a pair of angularly arranged plates secured at their adjacent ends to said angularly arranged sides of said block, one of said plates extending forwardly and the other rearwardly of said bar, a fork having its two arms disposed and secured to the opposite sides of the forward plate and its shank portion extending above the upper edge of the latter and provided with a cross handle bar, the lower ends of the arms of

said fork extending below the lower edges of the forward plate and provided with bearings, a driving wheel having its axle journaled in said bearings and provided with pedals, a pair of vertical bars disposed and secured to opposite sides of the rear plate and having their lower ends extending below the lower edge of the latter and provided with bearings, and a ground wheel

having its axle journaled in the last named 10 bearings.

In testimony whereof I have hereunto set my hand in the presence of two subscribing witnesses.

CHARLES HENRY WATERMAN.
